UNITED STATES PATENT OFFICE.

JOHN W. VAN ALSTYNE, OF VANCOUVER, WASHINGTON.

DIGESTER.

Application filed October 3, 1925. Serial No. 60,328.

To all whom it may concern:

Be it hereby known that I, JOHN W. VAN ALSTYNE, a citizen of the United States, and a resident of Vancouver, in the county of 5 Clarke and State of Washington, have invented a new and useful Digester, of which the following is a specification.

This invention relates generally to the paper industry, and particularly to digesters such as are employed for preparing 10 pulp by the sulfite process.

The first object of this invention is to prevent the accumulation of lime at the bottom 15 of the digester and in the attached discharge fitting.

The second object is to prevent the stoppage of the outlet at the bottom of the digester by the accumulation of lime, which stoppage would cause a great loss in time 20 and material and reduce the capacity of the digester.

The third object is to improve the quality 25 of the pulp prepared by admitting steam to the digester in a manner that a circulation of pulp and cooking acid will be set up and continued thereby, thus insuring against separation of lime from the cook and also against discoloration in the form of 30 blotches and spots which appear in the finished paper, due to improper mixing and undesirable reactions set up by over-heating in the discharge fitting, which condition is prevalent in the present type of digester.

The fourth object is to so construct the 35 digester that each and every cook can be completely discharged from the digester, thereby improving the quality of the pulp and increasing the capacity of a given size 40 of digester, besides eliminating the losses arising from clogged outlet fittings.

These, and other objects, will become more apparent from the specification following as illustrated in the accompanying drawing, in which:—

The figure in the drawing illustrates the 45 lower end of a typical form of digester in vertical section showing the present side inlet for steam, in dotted lines, which inlet is not necessary with my arrangement. The 50 main discharge valve and other well known parts and details are omitted. Only enough of the digester is shown to completely illustrate the invention.

Referring in detail to the drawing, there 55 is illustrated the usual flanged ring 10 on whose horizontal portion is mounted a ring

11 to which is secured the usual digester shell 12, which is lined with fire brick 13, for which the sleeve 14 on the ring 10 forms a footing. On the under side of the 60 ring 10 is attached an outlet or discharge fitting 15 to which is attached the flange 16 of the usual cutoff valve (not shown).

The usual side steam inlet 17, whose position is indicated in dotted lines, is not employed, but is merely capped over if present on the digester. The bottom steam inlet 18 does not open directly into the fitting 15 but is provided with a vertical pipe extension 19, which projects well up into the 70 digester, as shown, and discharges near the footing of the sloping sides of the bottom cone of the digester. In other words—the pipe 19 discharges entirely above the fitting 15 instead of into the bottom of same, as is 75 ordinarily the case.

The operation of the digester is similar to those in common use, but it is found in practice that very desirable results are obtained thereby. First the steam is applied 80 at a point within the digester where a circulation is set up which constantly agitates the entire contents 20 of the digester, causing the pulp and cooking acid to remain in a perfectly mixed state and preventing the 85 separation of these elements from each other and from the lime ingredient, which, being heavy, would naturally be deposited in the discharge fitting if a proper circulation was not maintained. If this lime is permitted 90 to settle within the discharge fitting 15 and steam is admitted only to the bottom of this fitting, naturally the concentrated heat will tend to bake the lime deposit within the 95 fitting until the discharge of the digester is completely stopped.

Furthermore, if the digester cannot be thoroughly cleansed after the discharge of its pulp that which remains is not improved by repeated processing, and if any portion 100 of the reprocessed pulp finds its way out in a later batch, it will not add to the quality of the paper formed therefrom, but will rather tend to produce a lower grade of 105 paper.

I am aware that in some instances steam has been admitted well up on the side of the digester. This, however, is also undesirable since it tends to agitate the pulp near the top of the charge but permits the remainder to lie undisturbed within the digester, during which time the heavier lime naturally 110

gravitates toward and accumulates in the discharge fitting. The greatest objection, however, resides in the fact that the cooking acid does not come in uniform contact with all of the wood, as should be the case.

I claim:

1. A digester for making sulfite pulp having, in combination, a container for pulp, said container having a conical bottom formed thereunder; a flanged elbow attached to said conical bottom; and a vertical steam inlet pipe passing through the outer side of said conical portion of the container.

2. A digester for making sulfite pulp consisting of a container for said pulp having a conical bottom formed therein; having a discharge fitting at the lower end of said conical bottom; and a steam inlet pipe pro-

jecting upwardly through said fitting and discharging near the lower end of said conical bottom above said fitting.

3. In a digester, the combination of a brick-lined container having a flanged conical bottom with a flanged outlet elbow attached to the bottom of said container 25 flange; said outlet having a side outlet formed on the bottom thereof for admitting live steam; and a pipe extension in said bottom outlet terminating at its upper end near the bottom line of the container cone 30 and adapted to deliver steam to the cook within said container without overheating the contents of the outlet fittings by maintaining a thorough circulation of the contents of the digester.

JOHN W. VAN ALSTYNE.
